Attorneys.

UNITED STATES PATENT OFFICE.

WILLIS D. SHERMAN, OF OMAHA, NEBRASKA, ASSIGNOR TO THE UNION HYDRAULIC DRAIN TILE COMPANY, OF SAME PLACE.

TRUCK.

SPECIFICATION forming part of Letters Patent No. 461,689, dated October 20, 1891.

Application filed December 11, 1890. Serial No. 374,361. (No model.)

To all whom it may concern:

Be it known that I, WILLIS D. SHERMAN, a citizen of the United States, and a resident of Omaha, in the county of Douglas and State of Nebraska, have invented certain new and useful Improvements in Trucks or Carriages for Handling Sewer-Pipes or Drain-Tile Molds; and I do hereby declare that the following is a full, clear, and exact description of the invention, which will enable others skilled in the art to which it appertains to make and use the same, reference being had to the accompanying drawings, which form a part of this specification.

15 My invention relates to trucks or carriages for handling sewer-pipe and drain-tile molds.

In the manufacture of concrete or cement pipe by machinery such as disclosed in the application filed by me of even date here-
20 with, Serial No. 374,356, for improvements in machines for making sewer-pipe and drain-
tile, the faucet end of the pipe, which is pro-
vided with a groove to receive the end of an
adjoining pipe, is formed first, the filling ma-
25 terial being fed into the mold and compacted
by means of tamping-bars. The mold used
in connection with such machines consists of
a contractile core, a shell, a bottom plate, and
cover, as described and shown in an applica-
30 tion for Letters Patent filed by me of even
date herewith, Serial No. 374,358. After com-
pletion of the sewer-pipe or drain-tile it is
necessary to remove the mold from the ma-
chine and reverse the same in order to strip
35 the shell from the pipe.

The object of the present invention is to provide a truck or carriage by means of which the mold may be readily removed from the machine, and which will so suspend or hold the said mold that its position may be readily reversed.

The invention consists in the novel construction and combination of parts, herein-
40 after fully described, and definitely pointed
45 out in the claim.

In the accompanying drawings, Figure 1 represents a side elevation of a truck or carriage constructed in accordance with my invention. Fig. 2 is a plan view of the same.
50 Fig. 3 represents detail views.

In the said drawings, the reference-
number 1 designates the wheels of the truck
or carriage, which may be of any suitable con-
struction. These wheels are mounted upon
spindles 2, secured to downwardly-depend- 55
ing lugs formed with or secured to the hori-
zontal bars 3. These bars may be of wood
or metal, as may be found most convenient
or desirable, and are provided at their front
ends with inwardly-projecting arms 4, pro- 60
vided with upwardly-projecting pins 5, screw-
threaded at their upper ends. The numeral
6 designates a transverse bar or plate pro-
vided with slots 7 at each end and having a
forwardly-projecting arm 8. The pins 5 pass 65
through the slots in plate 6, which is adjust-
ably attached to the bars 3 by means of the
nuts 9. Connected with the arm 8 is a for-
wardly-projecting lever 10, having handle 12.
The rear ends of bars 3 are provided with 70
hooks 13.

The operation is as follows: When the
mold is to be removed from the machine, the
truck is backed up to the same and the rear
ends of the arms 3 depressed by elevating 75
lever 10, so that the hooks 13 will engage with
the trunnions of the mold. The lever is then
depressed, causing the mold to be elevated,
and it can then be readily wheeled to any
point or place desired and the mold can be 80
reversed, the trunnions thereof serving as
pivots. In my said application, Serial No.
374,356, I locate the trunnions intermediate
of the bottom and the center of gravity, so that
there will be no difficulty in reversing the 85
position of the same. After having removed
and reversed the mold it is lowered to the
ground, the bottom plate removed, and the
shell unlocked and stripped from the tile.
The object in making the arms 3 adjustable 90
laterally is to allow the trucks to be employed
in connection with molds of varying dia-
meters.

Having thus described my invention, what I
claim is—

95 In a truck or carriage for handling sewer-
pipe or drain-tile molds, the combination,
with the wheels, the horizontal arms provided
with hooks at their rear ends and with in-
wardly-projecting arms at their front ends 100

having upwardly-projecting screw-threaded pins, of the transverse plate or bar having slots at each end, the binding-nuts, the arm formed with or secured to said transverse plate, and 5 the lever secured to said arm, substantially as described.

In testimony that I claim the foregoing as

my own I have hereunto affixed my signature in presence of two witnesses.

WILLIS D. SHERMAN.

Witnesses:

JOS. L. COOMBS,
BENNETT S. JONES.
